UNITED STATES PATENT OFFICE

WALTER SCOTT HARTMAN, OF CALUMET CITY, ILLINOIS

BOWLING ALLEY

Application filed November 22, 1927. Serial No. 235,014.

This invention has reference to bowling alley construction and aims to provide a novel construction which will be securely braced to withstand the strain to which a bowling 5 alley is subjected, the construction being such as to maintain the alley level at all times.

Another important object of the invention is to provide an alley of this type having means whereby the same may be raised or 10 lowered to facilitate leveling of the alley during installation of the alley, or for trueing the alley after it has been in use.

A still further object of the invention is to provide a bowling alley construction embodying an all steel under construction to 16 render the alley noiseless.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

Referring to the drawings:

Figure 1 is a plan view of an alley constructed in accordance with the invention.

30 Figure 2 is a fragmental plan view of an alley showing the alley timber and gutter timber removed.

Figure 3 is a fragmental plan view of the alley construction illustrating the bars at the 35 front end of the alley.

Figure 4 is an end view of the alley, parts thereof being shown in section.

Figure 5 is a sectional view taken on line 5-5 of Figure 3.

40 Figure 6 is an elevational view of the ends of the transverse brace bars.

Figure 7 is a side elevational view of the pit at one end of the alley, parts thereof being shown in section.

45 Figure 8 is an end elevational view of the alley.

Figure 9 is a perspective view of the adjusting disk.

50 Referring to the drawings in detail, the alley includes a pair of outer bars 5 that are

secured to the surface on which the alley is constructed, by means of the angle bars 6 that are provided with openings to receive the bolts 7 that secure the angle bars to the supporting surface.

Angle bars 8 are secured to the inner surface of the bars 5 and are also provided with openings to receive the securing members 9. Bolts 10 extend through these angle bars as well as the bars 5, to firmly secure the bars 5 in their upright positions.

Disposed in parallel relation with the bars 5 are bars 11 that are secured to the supporting surface by means of the angle bars 12. Connecting the inner bars 11 and disposed transversely of the alley proper, are supporting bars 13 which are of channel bar construction and arranged in pairs as shown by Figure 6 of the drawings, the bars of each pair being held in spaced relation by means of the filling timbers 14 and 14'.

The member 14 is in the form of a loose filler which lowers and covers opening 48 to prevent sound from traveling through openings 48 as alley is raised.

At the ends of the bars 13 are angle bars 15 which are secured to the bars 13 by means of bolts 16, there being provided bolts 17 extending through the vertical flanges of the angle bars 15 for securing the angle bars 15 to the bars 11, the bars being provided with elongated openings 18 for the reception of these bolts 17, to the end that the angle bars 15 as well as the transverse supporting bars 13 may be adjusted vertically to level the alleys and on which the alley timbers may rest in the formation of the alley.

Supported between each pair of bars 13 and disposed adjacent to the outer ends thereof, are the adjusting screws 19 that are mounted in bearings 20 secured to the inner surfaces of the bars 11, the threaded adjusting screws 19 operating in threaded bearing members 21, to the end that as the adjusting screws 19 are operated, the bars 13 will be raised or lowered, at the will of the operator, it being understood that the bearing members 21 are secured to both of the bars 13 as at 22.

Openings 23 are provided in the periphery of the adjusting wheel or disk 24 that is

secured at the lower end of the adjusting screw 19 associated therewith, to the end that a lever may be inserted therein to rotate the adjusting wheel 24 to rotate the screw in a manner as described to accomplish the adjustment.

Owing to the fact that the wheels or disks 24 extend through openings in the bars 11, it will be obvious that the wheels or disks 24 bear against the lower edges of the openings when the wheels or disks are rotated to raise the supporting bars 13.

Openings 25 are provided in the upper surface of the wheel 24 and are designed to accommodate the pin 26 that passes through the keeper 27 that is formed with an opening to receive the pin, with the result that after the wheel has been adjusted, the pin may be inserted to secure the wheel against movement.

Between the pairs of bars 13 and secured to the bars 11 by means of angle bars 28, are transverse bracing bars 29 which are also formed of channel bar material defining a flange 30 and holding bars 11 at a given distance apart.

The bars 5 and 11 at each side of the alley are held in spaced relation with each other by means of the channel irons 31 that are arranged in pairs throughout the lengths of the bars 5 and 11, the channel irons of each pair being supported in spaced relation with each other.

These channel irons 31 provide supports for the bars 32 which are of various types and have their upper edges beveled so that they define a curved surface for the reception of the balls which are used in bowling so that the balls may run to the pit at the rear end of the alley should they pass laterally from the alley proper.

Transverse angle bars 33 extend transversely of the pit and are disposed below the upper edges of the bars 11 that extend into the pit, the bars being covered by a metallic sheet material indicated at 34, which is covered with fiberboard or similar material, the fiberboard and plate being provided with openings so that foreign matter such as dirt and dust may fall therethrough.

Angle bars indicated at 35 are provided and have downwardly extended forward end portions 36 connected with the bars 5 at the rear ends thereof, the angle bars extending rearwardly as at 37 where they connect with the vertical angle bars 38, the same being secured by means of the transverse bar 39 that connects the angle bars at each side of the alley proper.

Metallic members 40 formed of sheet metal are secured to the angle bars 35 and 38, the same being provided with openings to receive bolts for securing the usual padded material to the walls of the pit for cushion-

ing the blows of the balls and pins which contact therewith.

At the ends of the cross bars 13 are angle bars 41 which are secured to bar 11 by means of the bolts 42 so that the cross bars 13 are held in vertical position but at the same time allowing for free movement of the bars 13 when they are being raised or lowered.

The members 43 and 46 and supporting bars 32 together with the spacing members 43 and 11 at the front and rear ends of the alley are provided with small openings to receive the pit board cushions. The angle bars 44 and 45 at each end of the alley are bolted to the angle bars 15 and are used to support alley timbers at the extreme end.

From the foregoing it will be seen that due to this construction, an exceptionally rigid bowling alley is provided, novel means being used for leveling the alley. It will further be noted that owing to the fact that the device presents an all steel under construction, the alley will be practically noiseless and the structure will have a greater resale value.

I claim:

1. A bowling alley construction including a pair of substantially wide spaced stationary side bars having elongated openings and forming the sides of the alley, an alley base including wide vertically movable transverse supporting bars to which the alley planks are secured, angle bars connecting the movable supporting bars, bolts extending through the angle bars and elongated openings to adjustably connect the alley base to the stationary side bars, and means for moving the alley base vertically.

2. A bowling alley construction including a pair of substantially wide spaced stationary side bars, an alley base including substantially wide transverse supporting bars to which alley planks are secured, threaded bearings on the transverse bars, threaded shafts extending into the threaded bearings to adjust the alley base vertically, adjusting wheels on the lower ends of the shafts to adjust the shafts, and said wide spaced stationary side bars having slots through which the adjusting wheels extend to permit the adjusting wheels to be operated to adjust the alley base, and means for holding the alley base in its positions of adjustment, said means including keepers adapted to engage said adjusting wheel and prevent rotation thereof.

In testimony that I claim the foregoing as my own, I have hereto affixed my signature.

WALTER SCOTT HARTMAN.
